DRAINER TRAY

Charles F. Molzen, Yardley, Pa., assignor to Rubbermaid
Sales Corp., Wooster, Ohio

Filed Nov. 1, 1972, Ser. No. 302,645

Term of patent 7 years

Int. Cl. D7—99

U.S. Cl. D7—188

FIG. 1

FIG. 2

FIG. 1 is a plan view of a drainer tray embodying my new design.

FIG. 2 is a side elevation thereof.

FIG. 3 is a sectional view on line 3—3 of FIG. 1.

FIG. 4 is an enlarged partial plan view thereof.

I claim:

The ornamental design for a drainer tray, as shown.
